[57] CLAIM

The ornamental design for an ice bucket or similar article, substantially as shown and described.

DESCRIPTION

FIG. 1 is a front elevational view of an ice bucket or similar article, showing my new design;

FIG. 2 is a side elevational view thereof, as seen from the right of FIG. 1;

FIG. 3 is a rear elevational view thereof;

FIG. 4 is a top plan view thereof, with a cover element removed to show interior detail;

FIG. 5 is a bottom plan view thereof;

FIG. 6 is a side elevational view thereof as seen from the left of FIG. 1; and

FIG. 7 is a sectional view of the cover thereof.
